US0D1092154S

(12) **United States Design Patent** (10) **Patent No.:** **US D1,092,154 S**
(45) **Date of Patent:** **** Sep. 9, 2025**

(54) **COOLER**

(71) Applicant: **Rivian IP Holdings, LLC**, Irvine, CA (US)

(72) Inventor: **Michal Jan Holcer**, Mission Viejo, CA (US)

(73) Assignee: **Rivian IP Holdings, LLC**, Irvine, CA (US)

(**) Term: **15 Years**

(21) Appl. No.: **29/930,300**

(22) Filed: **Feb. 28, 2024**

(51) **LOC (15) Cl.** **07-10**

(52) **U.S. Cl.**

USPC **D7/605**

(57) **CLAIM**

The ornamental design for a cooler as shown and described.

DESCRIPTION

FIG. 1 is a top, front, left side perspective view of a cooler, showing my new design.

FIG. 2 is a bottom, rear, right side perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof.

FIG. 8 is a bottom plan view thereof.

FIG. 9 is a top, front, left side perspective view of a cooler, showing my new design.

FIG. 10 is a bottom, rear, right side perspective view thereof.

FIG. 11 is a front elevational view thereof.

FIG. 12 is a rear elevational view thereof.

FIG. 13 is a right side elevational view thereof.

FIG. 14 is a left side elevational view thereof.

FIG. 15 is a top plan view thereof; and,

FIG. 16 is a bottom plan view thereof.

The broken lines in the figures show portions of the cooler that form no part of the claimed design.
